UNITED STATES PATENT OFFICE.

MAXWELL VIDAYER, OF NEW YORK, N. Y.

MACHINE FOR POINTING PINS.

1,362,763.

Specification of Letters Patent. Patented Dec. 21, 1920.

Application filed February 24, 1919. Serial No. 278,893.

To all whom it may concern:

Be it known that I, MAXWELL VIDAYER, a citizen of the United States, and a resident of the city of New York, in the county of 5 New York and State of New York, have invented certain new and useful Improvements in Machines for Pointing Pins, of which the following is a specification.

The present invention relates to improvements in machines for forming the points of pins.

The main object of the invention is to provide a machine of this character that is simple in construction and comparatively 15 inexpensive, and whereby the pins may be pointed in an easy and economical manner without excessive or extraordinary expenditure of time and labor and without requiring the exercise of any special skill on the 20 part of the attendants or operators such as is requisite where manual labor is employed in the manufacture of such articles.

With these and other objects in view, which will more fully appear as the nature 25 of the invention is better understood, the same consists in the combination, arrangement and construction of parts hereinafter described, pointed out in the appended claims and illustrated in the accompanying 30 drawings, it being understood that many changes may be made in the size and proportion of the several parts and details of construction within the scope of the appended claims without departing from the 35 spirit or sacrificing any of the advantages of the invention.

One of the many possible embodiments 40 of the invention is illustrated in the accompanying drawings, in which:—

Figure 1 is a plan view of a pin pointing machine constructed in accordance with the present invention; Fig. 2 is a section taken on line 2—2 of Fig. 1; Fig. 3 is a section taken on line 3—3 of Fig. 2; Fig. 4 is a 45 perspective view of a portion of the pin-carrier of the machine; and Fig. 5 is a perspective view of a detail of construction.

In the drawings, the numeral 10 indicates the frame of the machine, provided in its 50 sides 11 and 12 with bearings 13 and 14, respectively. In these bearings, which are in alinement, are rotatably mounted horizontally extending shafts 15 and 16, respectively, having a common longitudinal axis. 55 The inner ends of these shafts are juxtaposed,

meeting substantially in the center of the frame, and are provided with means to keep them in proper alinement. For this purpose, for instance, the inner end of the shaft 16 is reduced in diameter, as clearly 60 shown at 17, said reduced end extending into a cylindrical recess 18 in the shaft 15. Continuous rotation may be imparted to these two shafts in any suitable manner, for instance by chains 19 and 20, running over sprocket wheels 21 and 22, respectively, the sprocket wheel 21 being fixed to the shaft 15 and the sprocket wheel 22 to the shaft 16. 65

Upon the shaft 15 turns loosely a pin-carrier 23, in the form of a disk, that is provided with radially extending, equidistantly disposed notches 24 in its peripheral portion, the length of each notch being several times the diameter of a pin, and the width of each slot being slightly larger than the diameter of a pin. This pin-carrier is rotated from the shaft 15, to which is fixed for this purpose a pinion 25, in mesh with a gear 26, the latter being attached to a counter shaft 27, that is rotatably journaled 70 in bearings 28 on the sides of the machine frame. The ratio of the pinion 25 and gear 26 is 1:2 for a purpose hereinafter to be described. To the counter shaft 27 is fixed a gear 29, in mesh with a gear 30, that is secured to the pin-carrier 23. The ratio of the gears 29 and 30 is 1:1. 75

With the pin-carrier coöperate two pin-supports, denoted by the numerals 31 and 32. These supports are made in the form 80 of disks of equal diameter, one support being disposed upon each side of the carrier. The diameter of the pin-supports is substantially smaller than that of the pin-carrier, so that the pins within the notches 24 rest on the peripheral portions of the said supports. Both supports are fixed to the shaft 15 and rotate thus at a speed twice that of the pin-carrier. To the support 32 is adjustably secured, in the form of a 85 flange, a stop 33, to gage the positions in which the pins 34 are presented to a grinding wheel 35, which is fixed to the shaft 16. The peripheral portion of this grinding wheel is of proper bevel, to produce the desired amount of pointing of the pins. The grinding wheel is disposed at a slight distance from the pin-support 31, the ends to be pointed of the pins projecting beyond the last-mentioned pin-support onto the 100 105 110

bevel surface of the grinding wheel, which is disposed concentrically with the two pin-supports and the pin-carrier.

Around the upper part of the perimeter of each pin-support extends an arc-shaped spring band or strip 36. These bands are fixed to a support 37, that extends transversely of and is secured to the frame 10. The spring bands or strips are forced against the perimeter of the pin-supports by helical springs 38, bearing against the said bands and the frame 37. With each spring band coöperates a plurality of these helical springs, the latter being suitably spaced apart, as clearly appears from Fig. 3 of the drawings, and thereby dividing the respective spring band into a plurality of independently operating sections, as will herein-after appear. The frame 37 is adjustably secured to the main frame 10, and the spring band coöperating with the support 32 is adjustably mounted upon the frame 37, to permit of adjustment according to the size of the pins to be operated upon.

25 The pins to be pointed are fed by gravity into the notches 24 in the pin-carrier 23 from a chute 39, having an inclined bottom 40. This chute is supported by a standard 41, rising from the base plate 42, to which the frame 10 is attached. The side wall 43 of the chute is adjustably secured in relation to the opposite side wall thereof to accommodate pins of different sizes. In order to prevent more than one pin from entering a notch 24 in the pin carrier, there rise from the bottom 40 of the chute lugs 44, in alinement with the pin-supports 31 and 32. These lugs extend upward to the spring bands or strips 36 and are disposed from the periphery of the pin-carrier a distance that is slightly larger than the diameter of a pin.

40 The finished product falls into a chute 45, it being removed from the pin-carrier by a stripper 46, that projects from a standard 47 to points adjacent the periphery of the pin-supports 31 and 32.

The operation of the machine is as follows:—The pin blanks are placed into the chute 39, wherein they slide, one after other, 50 into the notches in the carrier 23, as the same rotate past the discharge opening in said chute. The inner ends of these notches are disposed inside the perimeter of the pin-supports, so that the pins may properly rest 55 on the pin-supports. As above-mentioned, the lugs 44 permit only a single blank to enter a notch. While the pin blanks are traveling in contact with the said lugs, they do not rest upon the pin-supports 31 and 32. 60 As soon as the pin-blanks have passed the lugs 44, the spring bands or strips 36 force the same against the rotating pin-supports, and since the latter rotate at twice the speed of that of the carrier, the said pin blanks 65 are not only advanced in the direction of the

arrow shown in Fig. 3 of the drawings, but also caused to rotate around their own axes. While the pin blanks are thus carried from the chute 39 to the strippers 46, their protruding ends, which are in contact with the rapidly rotating grinding wheel 35, are gradually pointed, the finished product being disengaged from the carrier by the strippers 46, falling by gravity into the chute 45.

75 The spring bands or strips 36 are continuously under the tension of the helical springs 38, the latter dividing the said bands into a plurality of independent portions, so that, if a thicker pin blank enters one of the notches of the carrier, it will not interfere with the proper operation of the device, for the reason that, as it travels along the said spring bands or strips, the latter are adapted to yield at any given point thereof, the springs 38 still forcing the said bands 80 into contact with the remaining proper sized pin blanks on the carrier.

85 The machine as herein set forth is especially well adapted for use in the manufacture of ordinary pins, but it is to be understood that the invention is not limited in its scope to its application to machines for the manufacture of pins, but may be, with equally good results, applied to machines for pointing cylindrical objects of any size, both 90 as to length and diameter.

95 The invention presents many advantages and improved results in its practical use in the manufacture of pins permitting them to be produced in a continuous operation and automatically, dispensing thus to a great extent with the handling of the product and various other manual operations which have heretofore been required in this art and which have greatly increased the cost of 100 the finished article.

105 It is obvious that, instead of the particular driving mechanism herein described, others may just as well be used without departing from the invention, which lies mainly 110 in the provision of a pin-carrier, in combination with pin-supports, that rotate in the direction of said carrier but at a considerably higher speed, at least twice the speed of said carrier, in combination with the 115 means for preventing more than one pin blank from entering a notch on said carrier, and the stripping means for disengaging the finished product from said carrier.

120 What I claim is:—

1. In a machine for pointing pins, the combination with a pair of rotatable disk-shaped pin-blank supports, of a rotatable disk-shaped carrier disposed between said supports and provided with transverse notches in its peripheral portion adapted to receive the pin-blanks, said carrier being of a larger diameter than said supports, means for positively driving said carrier at 125 130

- a speed lower than that of said supports, and spring pressed means for forcing said blanks against the perimeter of said supports.
- 5 2. In combination with the machine defined by claim 1, a chute for the blanks coöoperating with said carrier, and means adjacent said chute permitting a single blank only to enter a notch in said carrier.
- 10 3. In combination with the machine defined by claim 1, a stripping means for removing the finished product from said carrier.
4. In a machine for pointing pins, the 15 combination with a pair of rotatable disk-shaped pin-blank supports, of a rotatable disk-shaped carrier disposed between said supports and provided with transverse notches in its peripheral portion adapted to receive the pin-blanks, said carrier being of a larger diameter than said supports, the inner ends of said notches being disposed inside the perimeters of said supports, means for rotating said supports at a speed higher 20 than that of said carrier, and spring-pressed means for forcing said blanks against the perimeter of said supports.
5. In combination with the machine claimed in claim 1, a stop upon one of 30 said supports for engaging one end of each blank while on said carrier, the other end of said blank projecting beyond the other support, and a rotary grinding wheel adjacent said last-mentioned support and in 35 concentric relation thereto.
6. In a machine for pointing pins, the combination with a pair of rotatable disk-shaped pin-blank supports, of a rotatable disk-shaped carrier disposed between said 40 supports and provided with transverse notches in its peripheral portion adapted to receive the pin-blanks, said carrier being of a larger diameter than said supports, means for positively driving said carrier at a speed 45 lower than that of said supports, spring-pressed means for forcing said blanks against the perimeter of said supports, a chute for the blanks coöoperating with said carrier, means adjacent said chute permitting a single blank only to enter a notch in said carrier, a stop upon one of said supports for engaging one end of each blank
- while on said carrier, the other end of said blank projecting beyond the other support, and a rotary grinding wheel adjacent said 55 last-mentioned support and in concentric relation thereto.
7. In a machine for pointing pins, the combination with a pair of rotatable disk-shaped pin-blank supports, of a rotatable disk-shaped carrier disposed between said supports and provided with transverse notches in its peripheral portion adapted to receive the pin-blanks, said carrier being 60 of a larger diameter than said supports, means for positively driving said carrier at a speed lower than that of said supports, spring-pressed means for forcing said blanks against the perimeter of said supports, a stripping means for removing the finished product from said carrier, a stop upon one of said supports for engaging one end of each blank 65 while on said carrier, the other end of said blank projecting beyond the other support, and a rotary grinding wheel adjacent said last-mentioned support and in concentric relation thereto.
8. In combination with the machine claimed in claim 4, a stop upon one of said 70 supports for engaging one end of each blank while on said carrier, the other end of said blank projecting beyond the other support, and a rotary grinding wheel adjacent said last-mentioned support and in 75 concentric relation thereto.
9. In a machine for pointing pins, the combination with a pair of rotatable disk-shaped pin-blank supports, of a rotatable disk-shaped carrier disposed between said 80 supports and provided with transverse notches in its peripheral portion adapted to receive the pin-blanks, said carrier being of a larger diameter than said supports, means for positively driving said carrier at 85 a speed lower than that of said supports, a spring band extending around part of the perimeter of each support, and spaced springs acting upon said bands for forcing the blanks against the perimeters of said 90 supports.

Signed at New York, in the county of New York and State of New York, this 6th day of Febr., A. D. 1919.

MAXWELL VIDAVER.
